UNITED STATES PATENT OFFICE.

JAMES WILLIAM LEARY, OF ALLENDALE, NEW JERSEY, ASSIGNOR TO AUTOMATIC
PACKING & LABELING COMPANY, OF DURHAM, NORTH CAROLINA, A CORPOR-
ATION OF NORTH CAROLINA.

FEEDING AND WEIGHING MECHANISM.

1,283,227.

Specification of Letters Patent. Patented Oct. 29, 1918.

Application filed October 29, 1915. Serial No. 58,638.

To all whom it may concern:

Be it known that I, JAMES WILLIAM LEARY, a citizen of the United States, residing at Allendale, in the county of Bergen 5 and State of New Jersey, have invented a certain new and useful Feeding and Weighing Mechanism, of which the following is a specification.

This invention pertains to an improved 10 feeding and weighing mechanism, and is designed more particularly for use in connection with materials which are not susceptible of being handled by the various force-feed mechanisms now commonly employed. Certain materials are more or less 15 adhesive or adherent in their nature, and are incapable of being handled and weighed with that accuracy and precision necessary to produce packages of a given and uniform 20 weight.

The main object of the present invention is to produce a machine capable of securing such result, and with materials of the character just noted. To that end, gravity feed 25 is employed, and certain portions of the machine are agitated so that the material is caused to gravitate and pass from the source of supply through the feed chute, the feed 30 hopper, which bulks up the main charge and likewise controls the dribble or final charge, and then into the scale-pan, from whence it is discharged into a suitable receptacle or 35 container.

One embodiment of the invention is illus- 40 trated in the annexed drawings, a twin or double machine being shown, though, as will be readily appreciated, one, or three or more units, may be arranged as desired.

In the drawings:

Figure 1 is a side elevation of the mechanism, the gate of the hopper being opened 45 and in position to permit discharge of the material into the scale-pan;

Fig. 2 a vertical sectional view, on the line 2—2, of Fig. 6, the parts being in the same 50 relative positions;

Fig. 3 a vertical sectional elevation, on the line 3—3 of Fig. 6;

Fig. 4 a horizontal sectional view on the line 4—4 of Fig. 3;

Fig. 5 a rear elevation of the hoppers,

illustrating the mechanism for supporting the upper or elevated ends thereof and for agitating or oscillating the same;

Fig. 6 a sectional elevation of the front of 55 the mechanism, the hopper gate and scale-pan being omitted at the left;

Fig. 7 a top plan view of the hoppers and the allied mechanisms, the scale-pans being 60 omitted;

Figs. 8 and 9 elevations of the cams for 65 operating the scale-pan doors and the hopper valves or doors, respectively;

Fig. 10 a view similar to Fig. 3, showing 70 the parts in such relation that the hopper valve is closed and the scale-pan dumping;

Fig. 11 a detail sectional view of the hopper, with the discharge gate closed and the adjustable bulking diaphragm or plate ele- 75 vated;

Fig. 12 a detail sectional view on the line 12—12 of Fig. 1;

Fig. 13 a detail perspective view of the 80 hopper gate operating mechanism;

Fig. 14 a detail sectional view on the line 75 14—14 of Fig. 10;

Figs. 15 and 16 detail views of the scale- 85 beam mountings; and

Fig. 17 a detail of a modified form of 90 mechanism.

In the following description wherein, as above noted, two feed mechanisms and a scale or weighing mechanism for each are shown, similar reference numerals are employed to indicate like parts.

The supporting structure which usually 95 surmounts a suitable packing machine (not shown) comprises two side frames 1 and 2, each having a rearwardly extending bracket 3 and likewise forwardly extending brackets 4 into each of which extends and is secured the lower end of vertically disposed, depending posts or rods 5, secured at their upper ends to the ceiling or other suitable fixed support. Adjustably secured to the upper 95 portion of the rearmost pair of rods 5 is a pair of brackets 6, between which extends a cross-bar 7, having secured to it brackets 7* to which in turn are secured the feed chutes 8, opening into a suitable source of the material to be weighed and packed. The lower 100 end of each chute is provided with a flexible

skirt 9, which extends into the upper end of the inclined feed hopper, hereinafter described in detail. The height of the chutes and consequently the distance the skirt may 5 project into the hopper, may be regulated by simply adjusting the brackets 7^a up or down upon the rods 5.

Extending between the side frames 1 and 2 and the brackets 3 is a second cross-bar 11, 10 see Figs. 5 and 7, which bar in turn carries a casting 12 provided with a pair of bearings 13 for a shaft 14. Said shaft carries at each end a crank 15, the connection being a slotted one so that the effective length of the 15 crank or the throw thereof may be varied as necessary or desired. The outer end of each crank has a pin 16 extending into the same, the pins being secured in brackets 17 secured in turn to the lower portions of the upper 20 ends of the hoppers 18, said hoppers in the present instance being arranged in pairs and connected together by cross-bars 19. The hoppers, as will be noted, are open-topped, 25 box-like receptacles, set on an incline and closed at their lower discharge ends by gates 20. A rod 21 extends through and transversely of the hoppers, and embracing said rod are resilient or spring bars 22, three in 30 number (Fig. 6), which bars at their upper ends are secured to a cross-bar 23 secured to brackets 24, Fig. 2. Said brackets embrace a cross-rod 25, mounted in brackets 26^a secured to the forward pair of rods 5. The 35 resilient bars form spring hangers for the forward or discharge end of the hoppers.

Preferably, though not necessarily, the bottom of the hopper is provided with a stepped plate 26, by the employment of which the feeding forward of the material is 40 facilitated, and when present less motion or throw of the hopper is necessary to effect the proper feeding of the material.

Mounted within the hopper, adjacent the lower or discharge end, and extending 45 transversely thereof, is a plate 27, carrying at its upper end a vertically-disposed cross-plate or partition 28. Said plates are provided with side flanges 27^a and 28^a, which lie close to the side walls of the hopper and 50 prevent the flow of material through the hopper except such as passes beneath plate 27.

Extending transversely of the hopper 55 is a cross-bar 29, Figs. 2, 6, 7 and 12, in which there is adjustably mounted a pair of vertically-disposed rods 30, the lower ends whereof are sleeved and adapted to receive and support a cross-bar or rod 31. Said rod 31 at its ends forms the support for 60 brackets or ears 32, riveted or otherwise secured to the upper face of plate 27, the plate being thus hingedly sustained at its upper end. Springs 33 encircling rod 31 and having one end secured thereto and 65 the opposite end bearing against the adja-

cent vertical rod 30, tend to depress or throw the lower end of plate 27 downwardly. A spring, as 34, Fig. 2, may be employed in conjunction with springs 33.

An L-shaped arm 35, Figs. 6 and 7, is also 70 secured to the upper face of the plate 27, said arm carrying a bolt 36, which passes through a slot formed in the lower portion of a link 37. The upper end of the link is provided with a series of openings adapted 75 to receive a pin or bolt 38, which extends through a slot 39, formed in the inner end of a lever 40 which latter is journaled on shaft or rod 21 and secured to the upper portion of gate 20. 80

By means of the connections just set forth the height of plate 27 with reference to the bottom of the hopper may be regulated as desired. The plate performs a two-fold function; first, to limit the quantity of material which may be bulked in the hopper prior to opening gate 20, and second, to regulate and control the material as it is dribbled into the scale-pan after the main bulk is discharged from the hopper. By 90 this means the material may be accurately and expeditiously fed to the scale-pan which underlies the discharge end of the hopper. 85

Gate 20 of the hopper is normally drawn to its closed position through the medium 95 of a spring 41, Figs. 2, 6, 7 and 11, secured at one end to a post or pin 42 extending out from the side wall of the hopper, the opposite end being fastened to the lower end of an arm 43 formed as a part of a casting 44 100 secured to the side wall of the gate 20, said casting forming one of the gate-bearings journaled on shaft 21. To the opposite side there is secured a similar casting 45, see Figs. 3 and 13, having an inwardly and 105 horizontally extending latch arm 46, carrying at its outer end, on one side, a latch pin 47, and upon its opposite side a roller 48, all of which will be again referred to.

The scale-pan 49 underlies the discharge 110 end of the hopper, being mounted in the bifurcated end of a scale beam 50, which at its other end carries a weight 51, as usual. The knife-edge trunnion 52, see Fig. 16, of the pan finds its bearings in a block 53, the 115 parts being protected from falling waste material by a bracketed plate 54, secured to the beam and overlying the trunnion and block. The bearings for the scale beam are carried upon a cross-bar 55, see Figs. 1, 2, 120 3, 6 and 15, secured in the forward portion of the side frames 1 and 2.

The outermost bearing, 56, for each beam is of the usual type, and is provided with a bracketed plate 57, see Fig. 6, to prevent 125 ingress of material to the bearing.

The inner or adjacent trunnions of the beam, see Fig. 15, bear upon a common block 58, secured to bar 55, a plate 59, secured in the block separating the adjacent 130

trunnions so as to prevent interference. A plate 60 overlies these parts and prevents ingress of foreign material.

A rod 61 extends down from the bar 55 adjacent each scale pan (Figs. 2, 4 and 10) and a distance link 62 is pivoted to its lower end and to the pan adjacent its lower portion, whereby the scale-pan is caused to move up and down free of rocking or swinging motion.

The scale-pan is provided with a pair of hinged gates 63 and 64, to which, adjacent their fulcrums, are secured arms or levers 65, 66, said arms overlapping, see Fig. 1, one arm being slotted and into which slot extends a pin 67. A spring 68, secured at one end to the pan and at its other end to one of the arms, serves to draw the gates to their closed position and to maintain them closed against the weight of material dumped into the pan. A lever 69, fulcrumed upon a rod 70, supported in frames 1 and 2, overlies pin 67 and serves to open the gates when the full charge has passed into the scale-pan. Said lever carries a roller 71, which takes in a groove 72, (Fig. 8) of the cam 73, mounted upon a drive shaft 74, journaled in the side frames. Said shaft also carries a pulley 75, Figs. 1 and 6, a crossed belt 76, passing about the same and also about a small pulley 77 secured to the outer end of a counter-shaft 78. Said shaft has secured to it a second and larger pulley 79, about which passes a belt 80, the belt also passing about a small pulley 81, secured upon shaft 14, Fig. 5. Motion is thus imparted to shaft 78 and shaft 14, and through the latter and cranks 15 and their allied parts endwise reciprocating motion is imparted to the hoppers 18.

The hopper gate 20 is positively opened by a lever 82, Figs. 1, 3, 7 and 10, fulcrumed upon a stub shaft 83, secured in frame 1 (or 2), the free end of the lever overlying roller 48 and having connected thereto a link 84 connected at its lower end to the outer end of a second lever 85, fulcrumed on rod 70. Said lever 85 carries a roll 86, Fig. 9, working in the cam groove 87 of the cam member 88 secured to shaft 74. With the gate 20 closed, the parts stand in the positions shown in Fig. 10, at which time the scale-pan is discharging and a charge is being bulked in the hopper 18. As the scale-pan ascends, after the load is discharged, at which time lever 69 rises, the gates 63, 64 are closed through the action of spring 68. When the scale-pan is fully elevated, lever 82 begins its downward movement contacting with roller 48 and again opening gate 20. Said gate, at its lower portion, has secured to it a block 89, to which is fulcrumed a link 90, provided at its inner end with a slot 91. A pin 92 extends into said slot, the pin projecting outwardly from the lower

arm or member 93 of a three-armed lever, the arms being denoted by 93, 94 and 95. Said lever is fulcrumed upon a stud 96, secured to the side of the hopper. A spring 97 is connected to block 89 and to the lower end 70 of arm 93 and acts to draw the gate to its closed position. Arm 95 has secured to it a latch 98, which lies in the same vertical plane as pin 47, with which it coacts to hold the gate 20 open under certain conditions. 75 Arm 94 extends outwardly and is formed with a contact surface or member 99. Said member lies below and in line with a roller 100, mounted on a stud extending outwardly from a lever 101, fulcrumed on a stud 102 80 (Figs. 6 and 7) secured in the adjacent side frame. Said lever 101 has jointed to it by a knife-edge bearing or trunnion 103, a vertically-disposed bar 104, the lower end of which is secured to the scale-pan so that the 85 lever moves up and down with the scale-pan or vice versa. The lever at its opposite end has secured to it a contact plate or member 105, said plate under certain conditions contacting with the periphery of a constantly 90 rotating wheel or disk 106. Said disk (see Fig. 12) is secured to a gear 107, and rotates with the same upon a shaft 108, secured in the upwardly-extending arm of a rocker frame 109, the frame being journaled upon 95 shaft 78, which shaft has secured to it a gear 110 which meshes with gear 107.

To the lower, laterally-extending arm 111 of the rocker-frame there is secured a pin 112, Fig. 14, which extends through a slot 100 113 formed in the lower end of a link or bar 114, the bar at its upper end being pivotally secured to lever 82. A coiled spring 115, secured at one end to pin 112, and at its opposite end to a pin 116 attached to bar 114, 105 tends to draw arm 111 upwardly and consequently to rock the frame in the direction of plate 105, and to thereby bring the wheel 106 into contact with said plate, the effect being to draw the plate upwardly and to 110 force the opposite end of lever 101 downwardly. A stop pin 117, Figs. 1 and 12, extending outwardly from the upper end of rocker frame 109, contacts with an adjustable screw 118 as the rocker frame is tilted 115 and serves to limit the degree of frictional contact between the plate 105 and wheel 106. These contacting surfaces may be roughened or even toothed to insure proper coaction, as shown in Fig. 17.

The upward and downward movements of the scale-pan are arrested or limited by the outer trunnions 52 coming into contact with the upper and lower portions, respectively, of a bracket member 119, see Figs. 1, 6 and 10, secured to an arm or bracket 120 secured to the side frame 1 (and 2).

To hold the scale-pan in its upper position and to prevent vibration and descent thereof when the bulk charge is first deliv- 120 125 130

ered, there is secured to link 84 an arm 121, which, when the lever 82 and link 84 descend (see dotted line position in Fig. 3) contacts with the scale beam and temporarily holds it, the trunnion 52 at such time being held against the upper portion of bracket member 119.

The operation of the mechanism is as follows: Power being applied to the shaft 74, it 10 is transmitted through the belts to shaft 14, and a reciprocating motion is imparted to the hoppers 18, causing the material which is fed downwardly through the chute 8 and the skirt 9 thereof to be moved forwardly 15 in the hopper toward the gate 20. Where a high speed is imparted to the hopper, the plate 26 may be omitted, but where the speed is relatively low the stepped plate tends to feed the material forwardly beneath the 20 combined bulking and dribble plate 27. With the parts in the positions shown in Figs. 10 and 11 the plate is elevated, and being adjusted to the required height will cause the material to bulk up thereunder in an 25 amount nearly equal to the weight for which the scale-pan is adjusted. As will be readily appreciated, by varying the adjustment of this combined bulking and dribble plate, the quantity bulked may be regulated, and 30 immediately the gate 20 is opened the bulked charge will pass outwardly and thereupon the plate will descend to that position shown in Fig. 2 wherein a dribble feed is produced between the lower end of the plate and the 35 underlying plate 26, or the bottom of the hopper, when the plate is not employed.

Any form of chute may be used, and the construction will vary according to the nature and condition of the material being 40 weighed and passed to the packing machine.

The main object of the invention is to eliminate any forced feed mechanism, and to cause the material to be fed by its own weight, and to assist this action by vibrating 45 the hopper.

With the parts in the positions shown in Figs. 2 and 3, the hopper-gate 20 is open and the bulk of material is presumed to have passed into the scale-pan below, and 50 the diaphragm or plate 27 is brought to the position where a dribble feed is effected to add to the material already in the pan that amount requisite to produce the desired and accurate weight. As the scale-pan descends, it draws the bar 104 downwardly with it, thereby rocking lever 101 and throwing contact plate 105 into operative relation with the disk 106. This contact tends to force the scale downwardly, 55 and as this movement takes place the roller 100, carried by the lever 101, contacts with bearing surface 99 of the arm 94 and withdraws the latch 98 out of locking engagement with the pin 47, thereby permitting

the spring 41 to act to draw the gate to 65 its closed position. The gate in so moving, will raise the lever 40, and through the link 37 will elevate the bulking plate and return it to the bulking position. At the same time, spring 97 also tends to assist in closing 70 the gate, and moves link 90 to the right, causing the pin 92 to contact with the left-hand end of the wall of the slot 91, whereby the spring 97 becomes ineffective. Further movement of the gate, through the closing 75 spring 41, will rock the three-arm lever and carry the contact surface 99 away from the roller 100, or into the position shown in Fig. 10. When the scale-pan reaches its lowest position, the lever 69 comes into operation, and opens the gates 63 and 64, to 80 discharge the scale-pan. At such time, the trunnion 52 comes into contact with the lower member of the bracket 119, and further downward movement of the scale-pan 85 is prevented. When the pan is discharged the lever 69, through the operation of the cam, will be raised and the scale-pan will again move upwardly. In so doing, the contact plate 105 will be moved downwardly to the position shown in Fig. 3, and in the meantime the lever 82 will have been lowered to such an extent as to tilt the 90 rocker frame 109 to the right, and thereby carry the disk or wheel 106 out of the path 95 of said contact plate 105, whereby the upward movement of the scale-pan and the lever 101, and the downward movement of the contact plate 105 are not impeded or interfered with.

When the gate 20 is closed, the parts stand in the positions shown in Fig. 10, and while the scale-pan is moving upwardly to receive another charge of material, the lever 85 comes into action and through the link 84 draws lever 82 downwardly, contacting with the roller 48, and opening the gate 20, through the arm or lever 46. Prior to such time spring 115 is acting to tilt the rocker frame 109 and to throw the disk into 100 position where it may coöperate with the plate 105 when said plate begins to move upwardly at the beginning of the downward movement of the scale-pan. The continued downward movement of the lever 82, to 105 open the gate 20, causes the gate, through the link 90 and spring 97, to rock the three-arm lever and to throw the latch 98 over the pin 47 and thus hold the gate open. This movement of the three-arm lever elevates the bearing surface 99 and brings it into a position where the roller 100 may 110 coact therewith upon the descent of the scale after it has received its full charge, the roller forcing the arm 94 downwardly 115 and withdrawing the latch from the pin 47, whereby the gate is again released. This 120 cycle of operations is repeated for each 125

charge of material which is fed to the scale-pan.

As above noted, the spring 115 tends to rock the frame 109, and causes the pin 117 to contact with the adjustable stop screw or pin 118. When, however, the lever 82 begins its downward movement, or from the position shown in Fig. 1 (at which time the scale-pan is moving upwardly) the upper end wall of the slot 113 contacts with the pin 112 and throws the upper end of the rocker frame to the right, thereby drawing the contact disk 106 out of the path of movement of the plate 105, as above set forth.

The connection of the lever 101, through rod or bar 104, with the scale-pan and the positive actuation of the lever by the contact member 105 and wheel 106 as the scale-pan descends, prevents the scale from faltering and positively moves it down, and at the same time positively withdraws latch 98 from engagement with pin 47, thereby allowing gate 20 to close.

It is obvious that in so far as the generic invention is concerned, the structure may be varied in many details, without departing from the spirit of my invention and the broader claims are to be read with this in view.

Having thus described my invention, what I claim is:

1. A feed mechanism for weighing machines, comprising in combination a hopper; means for agitating the same; a movable plate located in the hopper; a gate for the hopper; and connections between said gate and plate for moving the plate so as to restrict the discharge of material from beneath the same when the gate is opened.

2. A feed mechanism for weighing machines, comprising in combination a hopper; means for agitating the same; a plate adjustably supported with reference to the bottom of the hopper; a discharge gate for the hopper; and connections between said gate and plate for moving the plate so as to restrict the discharge from beneath the same when the gate is opened.

3. A feed mechanism for weighing machines, comprising in combination a hopper; means for agitating the same; a plate adjustably supported with reference to the bottom of the hopper; a discharge gate for the hopper; and means controlled by the position of the gate for moving the plate toward and from the bottom of the hopper.

4. A feed mechanism for weighing machines, comprising in combination a hopper; a plate supported therein; a discharge gate; and means controlled by the position of the gate for determining the position of the plate relatively to the bottom of the hopper.

5. A feed mechanism for weighing ma-

chines, comprising in combination a hopper; a plate pivotally supported at one end; means acting to throw the other end of the plate downwardly toward the bottom of the hopper; a gate; and connections between said gate and the plate for elevating the movable end of the plate when the gate is closed.

6. A feed mechanism for weighing machines, comprising in combination a hopper; a plate mounted to move toward and from the bottom thereof; and means, acting to move the plate toward said bottom when the material bulked thereunder is discharged, whereby a dribble feed will be effected.

7. A feed mechanism for weighing machines, comprising in combination a hopper; a cross-bar mounted in the upper portion thereof; a plate; connections between said plate and bar; a spring tending to move the opposite end of the plate toward the bottom of the hopper; a gate controlling the discharge from the hopper; and connections between said gate and the free end of the plate.

8. A feed mechanism for weighing machines, comprising in combination a hopper; a cross-bar carried in the upper portion thereof; a pair of rods adjustably supported thereby; a plate pivotally supported at the lower ends of said rods; springs acting to throw the opposite free end of the plate toward the bottom of the hopper; a gate controlling the discharge of the hopper; and connections between said gate and the adjacent end of the plate for elevating the same when the gate is closed.

9. In a feed mechanism for weighing machines, the combination of an inclined hopper having a stepped bottom; means for reciprocating said hopper; a gate controlling the discharge from the hopper; and a combined bulking and dribble feed plate mounted in the hopper.

10. In a feed mechanism for weighing machines, the combination of an inclined hopper; a stepped plate in the lower portion thereof; means for reciprocating said hopper; a combined bulking and dribble feed plate mounted in the hopper above the stepped plate; a gate located at the lower discharge end of the hopper; and means interposed between said gate and the feed plate aforesaid for controlling the position of the latter.

11. In a feed mechanism for weighing machines, the combination of an inclined hopper; flexible supports sustaining the lower end thereof; a driven shaft located at the opposite end; and a crank mechanism interposed between said shaft and the upper end of the hopper for supporting said end and imparting a reciprocating motion to the hopper.

12. In a feed mechanism for weighing ma-

chines, the combination of an inclined hopper; flexible supports sustaining the lower end thereof; a driven shaft located at the upper end of the hopper; a crank, adjustable as to throw, carried by the shaft; and connections between said crank and the adjacent portion of the hopper.

13. In a weighing machine, the combination of a vibrating hopper; a scale-pan located in line with the discharge end thereof; a gate for the hopper; a latch for holding the gate open; and means under the control of the scale pan for releasing the latch upon descent of the pan.

14. In a weighing machine, the combination of a hopper; a scale-pan located in line with the discharge end thereof; a gate for the hopper; a latch fulcrumed on the hopper for holding the gate open; and positively-actuated power-driven means under the control of the movement of the scale-pan for releasing the latch upon the descent of the scale-pan.

15. In a weighing machine, the combination of a hopper; a scale-pan located in line with the discharge end thereof; a gate for the hopper; a latch fulcrumed on the hopper for holding the gate open; a releasing lever for said latch; connections between the lever and the scale-pan; and positively-actuated power-driven mechanism adapted to move said lever into unlatching position.

16. In a weighing machine, the combination of a hopper; a scale-pan located in line with the discharge end thereof; a gate for the hopper; a latch for holding the gate open; a latch-releasing lever; connections between one end of said lever and the scale-pan; positively-driven mechanism adapted to coact with the opposite end of the lever; and to positively move the same; and an arm extending outwardly from the latch in line with one end of the lever and adapted to be actuated by said lever when the scale-pan begins its downward movement.

17. In a weighing machine, the combination of a hopper; a scale-pan located in line with the discharge end thereof; a gate for the hopper; a spring for drawing the gate to its closed position; a three-arm lever fulcrumed upon the hopper; a latch carried by one arm of the lever; a contact member carried by another of said arms; and a pin carried by the third arm; a link connected to the gate and having a slotted connection with said pin; a lever connection between one arm of said lever and the scale-pan, said end overlying the contact member aforesaid; and means for raising the opposite end of said lever as the scale-pan begins to descend.

18. In a weighing machine, the combination of a hopper; a scale-pan located in line

with the discharge end thereof; a gate for the hopper; a spring serving to close said gate; a latch lever connected to the gate and movable therewith; a three-armed lever fulcrumed upon the hopper, one arm carrying a latch adapted to coact with the latch-lever, another carrying a contact member, and the third a pin; a link connected to the gate, having a slotted connection with said pin; a lever; connections between one end of said lever and the scale-pan, said end overlying the contact member aforesaid; a rocker frame; a constantly driven wheel carried by said frame, said wheel standing in line with one end of the last-named lever; and means for moving said rocker frame to bring said wheel into contact with the lever.

19. In a weighing machine, the combination of a hopper; a scale-pan; located in line with the discharge end thereof; a gate for the hopper; a spring serving to close the gate; a latch lever connected to the gate; a three-armed lever; a latch member carried by one arm and adapted to coact with the latch lever; a contact member carried by another arm; a pin carried by the third arm; a link connected at one end to the gate and having a slotted connection with the pin aforesaid; a lever; connections between one end of said lever and the scale-pan, said end of the lever overlying said contact member; a rocker frame; a constantly-driven wheel carried by said frame and standing in line with the end of the lever last mentioned; a third lever overlying the latch member; connections between said third lever and the rocker frame; and means for moving said third lever downwardly to thereby actuate the frame and to open the gate.

20. In a weighing machine, the combination of a scale; a rotating member; and connections extending from the scale to said rotating member, adapted to come into action as the scale-pan begins its descent and to positively control the downward movement or lowering thereof.

21. In a weighing machine, the combination of a scale; a rotating member; a lever adapted at one end to coact with said member; and connections between the opposite end of the lever and the scale-pan for positively controlling the downward movement or lowering of the latter.

22. In a weighing machine, the combination of a scale; means for locking the scale in its elevated position; means for releasing said means when the scale has received a bulk charge; and mechanism for positively controlling the descent of the scale when released.

23. A feed mechanism for weighing machines comprising in combination a bulking chamber; means for moving the same; a gate

normally closing said chamber; a scale; and means for controlling the movement of said gate.

24. A feed mechanism for weighing machines comprising a chamber adapted to receive and bulk the material to be weighed and likewise to effect a dribble feed of the material after the bulk is discharged; means

for moving said chamber to cause discharge of the material therefrom; a gate for said chamber; a scale pan; and means for actuating said gate.

In testimony whereof I have signed my name to this specification.

JAMES WILLIAM LEARY.
